METHOD OF FABRICATING A FINNED HEAT EXCHANGER

Richard W. Kritzer and Anthony F. Hoesel,
Chicago, Ill.

Application December 31, 1935, Serial No. 56,936

1 Claim. (Cl. 29—157.3)

One of the objects of our invention is to fabricate a finned heat exchanger of continuous tubing, the parallel reaches of which are placed at very close centers.

5 Another of the objects of our invention is to provide a finned heat exchanger in which the tubing is firmly gripped by the fins.

A further object of our invention is to provide a finned heat exchanger, which necessitates a 10 minimum amount of labor and machinery for the fabrication of the same.

Further objects of our invention include a finned heat exchanger having a very high rate 15 of heat absorption.

15 Referring to the drawings:

Figure 1 is an isometric view, looking upward, of a fin coil embodying our invention.

Figure 2 is an elevational view of a fin as used 20 in our invention.

25 Figure 3 is a plan view of a fluid conduit used in our invention.

Figure 4 is a vertical cross-section along line A—A, Figure 1.

Figure 5 is a cross-section along line B—B, 30 Figure 4.

Figure 6 is a cross-section of a return bend of the fluid conduit, Figure 3.

Figure 7 is a cross-section along line C—C, 35 Figure 6.

Figure 8 is a cross-section along line D—D, Figure 6.

Figure 9 is a modification of the fluid conduit shown in Figure 3.

Figure 10 is another modification of the fluid 40 conduit shown in Figure 3.

Figure 11 is a cross-section along lines E—E and F—F of Figures 9 and 10, respectively.

Figure 12 is a diagrammatic illustration showing a certain manner of pressing the tubing into 45 the fin apertures.

In the drawings:

Figure 1, a finned tube heat exchanger 1, comprises a fluid conduit 2 having an inlet 3 and an outlet 4, between both of which are a 45 plurality of parallel reaches joined by return bends 5.

Upon the parallel reaches of the fluid conduit 2, and between the opposite return bends 5, a multiplicity of spaced apart fins 6 have a frictional engagement with the fluid conduit 2.

50 The upper edges, of the fins 6, have slots 7 which frictionally engage longitudinal bracing bars 8 driven into the slots.

In Figure 2, a metallic fin plate 6 has slots 7 in each right-hand and left-hand upper corner.

55 The lower portion of the fin plate 6 has spaced

apart apertures 9, which are preferably made with round punches, offset sufficiently so that the opening 10 is substantially smaller than the diameter 11 of the apertures 9.

In Figure 3, the fluid conduit 2 is formed into 5 nested form by means of the return bends 5. It will be noted that the conduit material, at the return bends 5, is squeezed to a smaller dimension, at certain points, than the dimension of the conduit at the parallel reaches. The reason 10 therefor will be fully explained later.

In Figures 4 and 5, the lower portion, of a fluid conduit 2, is flattened with ridges 12 angularly disposed relative to the length of the parallel reaches of the fluid conduit 2. Fluid wells 15 13 lie between adjacent ridges 12.

In Figures 6, 7 and 8, the return bend 5 is formed, in a suitable bender, so that the section C—C is of comparatively elliptical form, for a purpose to be explained later, and the section 20 D—D is left of substantially its former shape, prior to the bending operation. The purpose of the change in section along lines D—D, as compared to the section of C—C, is because that in bending thin walled tubing, to a short radius 25 and without the aid of internal devices for preventing inward buckling of the tube walls during the bending operation, the tube walls at the inner radius of the bend will buckle inwardly, unless the accumulated stresses are released at 30 given points. We have found that bending dies, made to all the humps shown at D—D, to form during the bending operation, allow us to form $\frac{3}{8}$ " copper tubing, of ".032" thick walls, to commercially acceptable return bends of $\frac{5}{8}$ " radius 35 to the center of the tube.

In Figures 9 and 10, we show return bends 14, which are of the same cross-section as the tubing prior to bending. These return bends, on short 40 radius bends, are generally made with internal former mandrels, during the bending operation, to prevent buckling of the tube walls at the bends.

In Figure 11 is shown a cross-section of the conduit along lines E—E of Figure 9 and lines 45 F—F of Figure 10.

In Figures 7 and 11, the cross-sections shown should have a width less than the dimension of the openings 10 of the apertures 9 of the fin plate 6, Figure 2.

Having described the elements of the invention, we shall now describe the method of fabricating a coil in accordance with the invention.

Using $\frac{3}{8}$ " outside diameter copper tubing, we bend it, with suitable dies as mentioned previously, to the form shown in Figure 3.

Passing a strip of proper material through a suitable die, we form the fin plate 6 of Figure 2. For $\frac{5}{8}$ " outside diameter tubing, which we prefer to use, we punch the apertures 9 with a round die having a diameter of .640", which is .015" larger than the outside diameter of the $\frac{5}{8}$ " tubing used. The fin plate 6 is so positioned in respect to the punching die that the aperture 9 breaks through the edge of the fin plate 6, as shown in Figure 2, and produces an opening 10, which is approximately .531" in width.

Laying the formed conduit 2, of Figure 3, upon a flat surface, we then engage the return bends 5, at the right-hand side of Figure 3, at the lines 15 C—C of Figure 6, with the openings 10 of the apertures 9 of the fin plate 6, Figure 2.

Since the openings 10 are wider than the width of the tubing at C—C, the fin plate 6 readily drops into position, after which it is forced along 20 the tubing to its proper position.

In placing the fins along the conduit, in their proper spaced relationship, we employ spacers, which we prefer made of a hard wood although any suitable material may be employed.

25 After the coil is assembled, we have a series of spaced fins, with a spacer between adjacent fins. We now pass the assembly to a pressing machine, which is illustrated diagrammatically in Figure 12, in which a stationary table 15 provides a support for the finned tube heat exchanger 1, which is step moved along in the direction indicated by the arrow. A die 16, having projections 17 on its working face, moved up and down at intervals, presses the tubing conduit 2 to a D shape having angularly disposed 35 ridges along the flat portion of the D shape as shown in Figures 1, 4 and 5.

40 In pressing the tubing to a D shape, the tubing is pressed against the sides of the apertures 9 of the fin plates 6, and the fin plates 6 are firmly gripped by the conduit 2.

After the conduit tube 2 is pressed into all of the fins, the spacers, between adjacent fin plates 45 6, are then removed and the longitudinal bracing bars 8 are then driven into the slots 7, which

rigidifies the upper edges of the fins 6, making a comparatively solid assembly.

In certain cases, we may prefer to have return bends having a full tube cross-section and, in that case, we shall form the bends as shown in Figure 9, in which the section E—E is slightly flattened to a dimension less than .531", allowing the fin plates 6 to drop onto the conduit at these flattened portions, from which they can be moved to their respective positions.

10 In other cases, we may prefer to assemble the fins and spacers in a separate jig and then lay the conduit tube 2 into the assembly, engaging all the fin plates 6 simultaneously, without the necessity of moving the pin plates to their respective positions after dropping them onto the tube at the flattened sections. In this case, we shall flatten the entire length of the parallel reaches, joined by the return bends, as shown in Figure 2, to a dimension less than .531", which 20 is the width of the opening 10 in the fin plates 6, Figure 2.

25 While we have described preferred forms of the invention, it is understood that departures from the same may be employed without departing from the spirit and scope of the invention, which is limited only to the following claim.

We claim:

The method of manufacturing a heat exchanger which comprises preforming a conduit 30 with parallel courses joined by return bends, punching fin plates with apertures breaking through an edge of the fin plates, the said apertures having a narrower width at the said edge than the aperture width at some point within the 35 said fins, deforming the said conduit to a width less than the aperture width at the edge of the said fin, assembling the said fins upon the conduit by placing them upon the said conduit with the apertures engaging the said deformation, 40 moving the fins into their proper spaced relationship upon the said conduit and then flattening the conduit to tightly grip the walls of the apertures.
